UNITED STATES PATENT OFFICE.

DANFORTH FLETCHER ALVORD, OF WINSTED, CONNECTICUT, ASSIGNOR TO THE EMPIRE KNIFE COMPANY, OF WINSTED, CONNECTICUT, A CORPORATION OF CONNECTICUT.

DESIGN FOR A BLADE FOR GRAPE-FRUIT AND ORANGE KNIVES.

48,236.

Specification for Design.

Patented Nov. 30, 1915.

Application filed May 12, 1915. Serial No. 27,727. Term of patent 14 years.

To all whom it may concern:

Be it known that I, DANFORTH FLETCHER ALVORD, a citizen of the United States, and a resident of Winsted, in the county of Litchfield, State of Connecticut, have invented a new, original, and ornamental Design for a Blade for Grape-Fruit and Orange Knives, of which the following is a specification, reference being had to the accompanying drawing, forming part thereof.

In the drawings, Figure 1 is a side view of a knife showing my new design. Fig. 2 is an edge view thereof.

I claim—

The ornamental design for a blade for grape-fruit and orange knives as shown.

DANFORTH FLETCHER ALVORD.
